GARMENT POCKET

Application filed June 10, 1931. Serial No. 543,410.

My present invention relates to garments and the tailoring thereof and more particularly to the making of patch pockets for men's and women's apparel, and it has for its object to provide an improved patch pocket which will be as slightly as the ordinary patch pocket, but which will be much stronger and will hold its shape much better.

To these and other ends, the invention relates in certain improvements and combinations of parts, all as will be hereinafter more fully described, the novel features being pointed out in the claims at the end of the specification.

15 In the drawings:

Fig. 1 is a front view of a fragment of a garment having a patch pocket applied thereto constructed in accordance with and illustrating one embodiment of my invention, the 20 lower portion of the outer wall being broken away;

Fig. 2 is a similar view showing the relative arrangement of the inner elements of the pocket in dotted lines;

25 Fig. 3 is a front view of the pocket with the flap raised and illustrating one method of stitching the same;

Fig. 4 is a front view of the pocket illustrating another method of stitching;

30 Fig. 5 is an enlarged transverse section with one edge of the patch free or as it would appear before stitching;

Fig. 6 is a vertical section on the line 6—6 of Fig. 4 on a larger scale;

35 Fig. 7 is a similar fragmentary section on the line 7—7 of Fig. 4;

Fig. 8 is a further enlarged fragmentary section taken on the line 8—8 of Fig. 4, and

40 Fig. 9 is a similar section taken on the line 9—9 of Fig. 3.

Similar reference numerals throughout the several views indicate the same parts.

In the usual construction of patch pockets, as the name implies, the patch of the same material is simply stitched at its edges against the face of the garment to produce a pocket jointly therewith. Such suiting and overcoat materials stretch easily with the result that the pocket ultimately assumes a permanent bulge, particularly if large or

heavy objects are carried therein. With my invention, I prevent this by entirely taking the strain off of the patch, transferring it to non-stretchable interior elements associated therewith.

Referring more particularly to the drawings, 1 indicates the body of the garment and 2 the patch. The latter has a lining 3 of non-stretchable material which is stitched to its inturned upper edge at 4. Opposite to and beneath this lining piece 3 is placed another lining piece 5, the upper edge of which may be joined at 6 to the usual satin facing 7 for the flap 8 when a flap is used. In constructing the pocket, lining piece 5 is laid upon the garment and lining piece 3, which is a little smaller and which has already been sewed to patch 2 at 4, is superposed thereon together with the patch. These three parts are then basted in position, as indicated at 9, the edge of the patch is raised at the basting, as shown in Fig. 5, and the two lining elements are machine sewed at 10 to each other and through the body element 1.

The patch 2 which is, of course, larger than and overlaps the lining elements is then stitched at its edges directly to the body 1, either by a straight machine stitch, shown at 11 in Figs. 3 and 9, or by felling, as indicated at 12 in Figs. 4 and 8. It will thus be seen that the entire weight and strain of articles placed in the pocket are taken by the lining elements and there is no strain on the patch itself. To keep the patch from stretching at its edges from any cause, I prefer to stitch a tape 13 to its under edge. While its lateral edges may come so close to the lining seam 10 as to barely cover it, I prefer to run the bottom edge quite a distance beyond the lower edges of the liners. By doing so, the stitched lower edge of the patch is carried farther away from the bottom of the actual pocket, so that no strain can be imposed thereon and objects resting against the bottom of the pocket as formed by the pieces 3 and 5 do not cause so perceptible a bulge in the patch.

The flap 8 carrying the facing 7, which is attached to the lining 5 at 6 as before described, is, of course, sewed in place at the 100

time the stitching 10 is done as far as the facing 7 is concerned and then felled or stitched to the body 1 at the time the patch is sewed in place.

5 In Fig. 7, I have illustrated an inner change pocket that can be worked into this same construction. It is indicated at 14 and its back wall is sewed to the facing 7 at 15 instead of the lining 5 being attached at this point. Its 10 front wall is doubled over the upper edge of the lining 5 and sewed thereto at 16.

If desired, my improved pocket may be 15 made with a single lining instead of a double lining and still provide the advantages I have set forth with respect to relieving the wool or other stretchable patch from strains. In such case, lining 3 is retained and sewed to the body 1 as before so that the pocket walls 20 comprise this non-stretchable piece reenforcing the patch as the outer wall and the body 1 of the garment as the inner wall.

I claim as my invention:

1. In a patch pocket, the combination with 25 a garment body, of a pair of linings stitched together and to the body on the outer side thereof in superposed relationship to form a pocket, and a patch overlying the linings and 30 stitched to the body independently thereof at the sides and bottom and to the upper edge of the outer lining at its top.

2. In a patch pocket, the combination with 35 a garment body, of a pair of linings stitched thereto in superposed relationship to form a pocket, and a patch overlying the linings and stitched directly to the body independently 40 thereof at the sides and bottom and to the upper edge of the outer lining at its top, the stitching of the patch at its bottom being removed a substantial distance from the lining stitching so that the weight of articles sustained by the linings is not communicated to the patch.

JOHN P. BACCARO.
